UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING MACHINE.

Application filed June 3, 1921. Serial No. 474,700.

To all whom it may concern:

Be it known that I, GEORGE A. SEIB, citizen of the United States, and resident of Ilion, in the county of Herkimer and State 5 of New York, have invented certain new and useful Improvements in Typewriting Machines, of which the following is a specification.

My invention relates to typewriting machines and more particularly to the type 10 actions thereof.

In typewriting machines wherein the pivoted type bars are mounted in a segmentally arranged series, it has been found difficult to provide sufficient room in which to mount 15 the requisite number of type bars and yet provide sufficient room between them in the basket, so that in operation conflict between adjacent bars may be avoided. This is particularly true where the entire series of bars 20 are mounted side by side with their pivotal centers in a single arc or plane, as for example where the type bars are mounted in guide slots of a segment to turn on a single 25 pivot wire, with all parts of the latter disposed in the same plane.

The main object of my present invention is to provide simple and efficient means by which these difficulties may be overcome.

30 A further object of the invention is to enable the features of my invention to be incorporated in existing forms of typewriting machines without material modification thereof and without modifying the appearance of the machine.

To the above and other ends which will hereinafter appear, my invention consists in the features of construction, arrangements of parts and combinations of devices 40 set forth in the following specification and particularly pointed out in the appended claims.

In the accompanying drawings wherein like reference characters indicate corresponding parts in the various views,

45 Figure 1 is a fragmentary fore and aft vertical sectional view of a typewriting machine embodying my invention.

Figure 2 is a detail fragmentary front 50 elevation of a portion of the same.

Figures 3 and 4 are detail fragmentary plan views, partly in section, and showing two left-hand and two right-hand type bars, respectively.

Figure 5 is an enlarged detail diagrammatic view illustrating two of the type bars, the type bar guide and segment, and the planes of the cuts of some of the guide slots (not shown) at the right-hand side of the segment. 55

Figure 6 is an enlarged diagrammatic view illustrating the planes of cuts of the guide slots and where they cross the median line of the segment. 60

Figure 7 is a diagrammatic view drawn 65 to the same scale as Fig. 6 and showing some of the slots at the right-hand side of the segment and the type bars mounted therein.

I have shown my invention in the present instance embodied in an Improved No. 10 70 Remington machine in which the invention may be incorporated with but slight modification of the machine as it now exists. It should be understood however that the invention is not restricted to its embodiment in 75 such machines, but may be employed in various styles of typewriting machines wherever found available.

In the accompanying drawings, I have illustrated only so much of the machine as 80 may be necessary to arrive at an understanding of the invention.

Referring more particularly to Figs. 1 and 2, it will be seen that the frame of the machine comprises a base *a*, corner posts *b*, 85 and a top plate *c*, over which a carriage (not shown) travels from side to side of the machine and carries a platen *d*. A segmentally arranged series of upwardly and rearwardly striking sheet metal type bars are 90

mounted in guide slots in a type bar segment *e* on a pivot wire *f* carried by the segment. The arc-shaped pivot wire is disposed in an upright plane, and all parts thereof are arranged at a uniform distance 95 from the point of convergence of the type bars. From an inspection of Fig. 2, it will be seen that the distance between adjacent slots in the segment gradually increases from the center to the sides of the system. 100

Each type bar moves from its segmental type rest *g* to the common printing point through about 90°. In moving to the printing position each type bar enters between opposite jaws of the usual type bar center 105 guide *h* secured to the segment *e*. The type bars may be actuated by any suitable means, those shown in the present instance comprising

ing spring returned key levers *i* and bell crank sub-levers *j*. Each key lever is fulcrumed on a bar *k* fixed to the base of the machine and is pivoted at *l* to the associated 5 sub-lever *j*. Each sub-lever is pivoted on a pivot wire *m* carried by a cross bar *n* fixed to the base of the machine. The upper end of each sub-lever carries a headed pin *o* which enters a slot *p* in the heel of the companion type bar. A segmental universal bar *q* supported for backward and forward movements on the segments is actuated by contacts *r* on the type bars. A rearward 10 movement of the universal bar *q* transmits movement through arms *s* on said universal bar to arms *t* on a rock shaft *u*, and from a centrally disposed arm *v* on the rock shaft to a link *w* to actuate the carriage escape- 15 ment, as disclosed in the patent to Oscar 20 Woodward, No. 1,342,489, dated June 8, 1920.

The parts thus far described are the same as those employed in the Improved No. 10 Remington machine. In said machine, however, the guide slots in the type bar segment are all cut in radial planes which correspond to the radial planes of movement of the body portions of the type bars, all of 25 said planes radiating from a common point of convergence of the type bars.

30 In accordance with my present invention I propose to maintain the gradually increased spacing of the slots from the center to the sides of the system, but to cut the guide slots, or some of them, in non-radial planes and to bend the body portion of each bar, thus mounted, laterally of the plane of its slot. The result of this is that the body portion 35 of each of said bars thus mounted, will not move in the plane of movement of its heel, but will converge at a common center and the laterally bent body portions of the type 40 bars will fan upwardly when at rest in the basket as will hereinafter more clearly appear.

45 In carrying out my invention in the present instance, and in accordance with the specific showing of its embodiment disclosed herein, it is intended that all of the forty-two type bars shall be mounted in non-radial slots as specified, although only a few 50 of the type bars are illustrated to simplify the drawings.

In order that the position of each type bar and its guide slot may be identified 55 I have indicated the type bars by the reference numerals 1' to 42' respectively, depending on the position of the type bar in the segment, and beginning with the left-hand terminal type bar designated by the reference 60 numeral 1', and ending with the right-hand terminal type bar designated by the numeral 42'. The forty-two corresponding 65 guide slots, counting from left to right, or the lines indicating the planes in which said slots are cut, are designated respectively by

the reference numerals "1 to 42". Thus the numeral 1 indicates the left-hand terminal guide slot (or the line which indicates the plane thereof) for the left-hand terminal type bar 1', whereas the right-hand slot, or 70 the line indicating its plane, is indicated by the numeral 42; each intermediate slot being designated according to its location and the number of the type bar received therein.

Figures 6 and 7 are to be read together, 75 and both being drawn on a scale of about ten times actual size, the sheets should be placed so that the lines 42, for example, on both figures are in alignment and are separated, so that the distance from the upper 80 end of the line 42 in Fig. 6 will be about thirty inches from the lower end of the line 42 in Fig. 7.

From these views it will be understood that each of the guide slots at each side of the segment is cut in a non-radial plane, each plane crossing the median line *x* of the segment at a different point and at a different distance from and below the printing point, as will hereinafter clearly appear. After each type bar is mounted in place in its guide slot, it is bent laterally of the plane of said slot, as indicated at *y* in Fig. 2, so that the body portions of the type bars converge at a common point *z* and all are properly received in the type guide *h*, and strike at a common printing center. As each type bar returns to and remains in a state of rest in the basket it assumes a different and higher position from what it would if mounted in a radial slot in the ordinary manner. Instead of the body portion of each bar extending in a straight line fore and aft of the machine when at rest, the bars are slightly fanned 100 in opposite directions from the center to the sides of the system, so that each type bar remains deflected slightly away from its adjacent bar, as indicated in Figs. 3 and 4. The type carrying ends of the terminal bars 105 are therefore at a higher elevation in the basket than they would be if mounted in radial slots. It follows that more room is provided in the type rest or basket for the system of type bars, and that a greater space 110 is provided between each pair of adjacent bars to avoid the liability of conflict between them in their movement towards and from the type rest, and at points adjacent thereto.

The particular layout of the slots in the 115 present instance is best indicated from a consideration of Figs. 6 and 7 read together in the manner hereinbefore described. It has been explained that the guide slots on each side of the median line *x* of the segment are cut in non-radial planes, each plane crossing said line at a different point. The plane of each terminal slot 1 or 42 crosses the line *x* at the lowest point or at a point furthest removed from and below the 120

115

120

125

130

printing point, whereas the planes of the remaining slots cross said line x at successively higher points, or nearer to the printing point, as the center of the system of type bars is approached. It also will be understood that the planes of each pair of corresponding guide slots at opposite sides of the segment, as 1 and 42 for example, intersect or converge at the median line x of the segment, and that the point of intersection or convergence of the planes of each pair of corresponding slots differs from that of every other pair of corresponding slots. It will be seen, moreover, that some of the planes indicated by the lines 1 to 21 converge at the left of the median line x , or at that side of the line x where the corresponding slots are located. In a like manner some of the lines 22 to 42 converge at the right of the median line x , or at that side of the line x where the corresponding slots are located.

If we assume that the distance on the line x from the lowest point of convergence of the planes 1 and 42, to the highest point on the line x where the planes 21 and 22 converge is 2.1 inches in Fig. 6, or .21 of an inch in a full-size machine, then the off-set or non-radial cutting of the guide slots in the manner indicated will result in giving an additional space (over that ordinarily produced by the radial mounting of the bars) of .010 of an inch between type bars, or an additional space of .210 of an inch divided between twenty-one type bars at each side of the median line of the segment, or a total additional space of .420 of an inch. Of course the figures given above are merely illustrative and may be widely deviated from, as may also the number of type bars employed, forty-four bars being employed in some instances. Moreover, while I have referred to each of the type bars at each side of the segment as being mounted in a non-radial plane, it may, in practice, be found sufficient to thus mount only some of the type bars, the others being mounted or arranged in radial planes. For example, it may be found to be unnecessary to mount some of the type bars near the center of the system in non-radial slots. Where such radial slots are cut, say, for example, the two or more for the center bars of the system, the heel of each such bar will move in the same plane as the body portion thereof, the body portions of the bars and the planes of their slots converging at the point z where the bars converge and where each bar is bent to properly enter the type guide, the latter point being indicated at z' .

My invention as defined by some of the broader claims of the present case, is included with other devices in the constructions disclosed in my co-pending application, Sr. No. 476,768, filed June 11, 1921,

the claims of said co-pending application being restricted to features not disclosed herein.

From the foregoing it will be understood that in the construction as shown and described in the present instance, each type bar may be said to comprise a heel or pivot end portion z^2 included between the bend y and the rear end of the bar; a shank or body portion z^3 between the bends y and z' , and a stem z^4 from the bend z' to the free end of the bar, and on which stem the type block z^5 is mounted. It will be seen, moreover, that the stem z^4 is bent laterally at an angle to the body portion or shank z^3 , and that the latter has a slight lateral bend y between said shank and the pivot end portion z^2 , so that each portion z^2 , z^3 and z^4 lies in a different plane and each shank z^3 swings to a common center z , whereas its pivot end portion z^2 swings in a plane divergent from said common center.

Various changes may be made without departing from my invention.

What I claim as new and desire to secure by Letters Patent, is,

1. In a typewriting machine, a series of type bars all pivoted in an arc in the same plane and the body portions of all of which converge when in printing position at a common center between said arc and the printing point, the distance from the pivotal center of a bar to said common center being uniform for all of said bars, and the heel or pivoted end portion of a terminal bar swinging in a non-radial plane that crosses the median plane of the series of bars between said common center and said arc and nearer the arc than the planes of the heels of any of the intermediate bars cross said median plane.

2. In a typewriting machine, a series of segmentally arranged type bars pivoted in an arc in a single plane, the planes of movement of the heels of corresponding bars at opposite sides of the series converging, the point of convergence of the said planes of one pair of corresponding bars differing from that of another pair of corresponding bars and the point of convergence nearest the arc being that of the planes of the heels of the terminal bars, the body portions of all of said type bars converging at a common center, the distance between said common center and the pivotal centers of the different bars being uniform.

3. In a typewriting machine, the combination of a series of pivoted type bars, and a segment having bearing slots in which said type bars are mounted, at least one of said bearing slots being a terminal non-radial slot the plane of which crosses the median plane of the segment nearer the pivots of the bars than do the planes of any of the intermediate slots.

4. In a typewriting machine, the combination of a series of pivoted type bars, and a segment having bearing slots in which said type bars are mounted, a plurality of 5 said slots in the same half of the segment being non-radial, one of said non-radial slots diverging from the radial more than another, and the body portion of each bar that is mounted in a non-radial slot being 10 bent laterally of the plane of its slot and all of said type bars converging at a common center.
5. In a typewriting machine, the combination of a series of pivoted type bars, and a 15 segment having bearing slots in which said type bars are mounted and guided, the planes of all the slots at the same side of the segment cutting different points in the median plane of the segment, the plane of 20 the slot of the terminal bar at said side cutting the median plane at a more remote point from the printing center than the other planes at that side.
6. In a typewriting machine, the combination of a series of type bars pivoted in an 25 arc, and a segment having bearing slots in which said type bars are mounted, the planes of all the slots at the same side of the segment cutting different points in the 30 median plane of the segment and the plane of each terminal slot cutting said median plane nearest said arc, and all of said type bars converging at a single point in the median plane of the segment.
- 35 7. In a typewriting machine, the combination of a series of pivoted type bars, and a segment having bearing slots in which said type bars are mounted, the planes of some of the slots at one side of the median plane 40 of the segment converging to a point at that side of said median plane.
8. In a typewriting machine, the combination of a series of pivoted type bars, and a segment having bearing slots in which said 45 type bars are mounted, the planes of some of the slots at one side of the median plane of the segment converging to a point at that side of said median plane, and the said planes of some of the slots at the opposite 50 side of the segment converging to a point at that side of said median plane.
9. In a typewriting machine, the combination of a series of pivoted type bars, and a segment having bearing slots in which said 55 type bars are mounted, the planes of some of the slots at one side of the median plane of the segment converging to a point at that side of said median plane, and the said planes of some of the slots at the opposite 60 side of the segment converging to a point at that side of said median plane, whereas said planes for other bars converge at the median plane of the segment.
10. In a typewriting machine, the combination of a series of type bars pivoted in an 65

arc, and a segment having bearing slots in which said type bars are mounted, the planes of the slots of each pair of corresponding bars at opposite sides of the segment converging at the median plane of the segment and said planes of the slots for no two such pairs of bars converging at the same point in said median plane, the planes of the terminal slots converging at said median plane nearest said arc. 75

11. In a typewriting machine, the combination of a series of pivoted type bars, and a segment having bearing slots in which said type bars are mounted, the planes of the slots of each pair of corresponding bars 80 at opposite sides of the segment converging at the median plane of the segment, the said planes of the slots for different pairs of corresponding bars converging at different points along said median plane and at increasing distances from the printing point. 85

12. In a typewriting machine, the combination of a series of pivoted type bars, and a segment having bearing slots in which said type bars are mounted, the planes of the slots of each pair of corresponding bars 90 at opposite sides of the segment converging at the median plane of the segment, the said planes of the slots for different pairs of corresponding bars converging at different points along said median plane and at increasing distances from the printing point, the planes of the slots for the pair of terminal bars converging at a point in the median plane furthest from the printing point, and the planes of the 100 slots for the pair of corresponding bars nearest the center of the segment converging at a point nearest to the printing point. 105

13. In a typewriting machine, the combination of a series of pivoted type bars, and a segment having bearing slots in which said type bars are mounted, the planes of the slots for the two terminal bars converging at a point in the median plane of the segment which point is different from the point or 110 points of convergence of planes of other slots, and which is the most remote from the printing point.

14. In a typewriting machine, the combination of a series of pivoted type bars, and a segment having bearing slots in which said type bars are mounted, the planes of the slots for the two terminal bars converging at a point in the median plane of the segment which point is different from the point or points of convergence of the planes of other slots, and which is the most remote from the printing point, the body portions of all of the type bars converging at a single point and the distance from said last 125 mentioned point of convergence to the pivotal centers of the type bars being uniform throughout.

15. In a typewriting machine, the combination of a series of type bars, an arc-shaped 130

- pivot wire on which said type bars are pivoted, and the center of which is coincident with the point of convergence of the type bars, a segment having bearing slots in 5 which said type bars are mounted, the plane of a bearing slot for at least one of said type bars being non-radial and crossing the median plane of the segment between said point of convergence and the pivot wire.
16. In a front strike typewriting machine, the combination of a series of upwardly and rearwardly striking type bars the body portions of all of which converge at a common center below the printing point, and a segment having bearing slots in which said type bars are pivoted, the plane of a terminal slot being non-radial and crossing the median plane of the segment below said common center where the type bars converge 15 and at a point more remote therefrom than the planes of any of the intermediate slots.
17. In a front strike typewriting machine, the combination of a series of upwardly and rearwardly striking type bars all pivoted 20 in the same upright plane and the body portion of all of which converge at a common center below the printing point, the distance between the pivotal center of a type bar and said common center being uniform for all 25 of said type bars, and a segment having bearing slots in which said type bars are pivoted, the plane of a terminal slot being non-radial and crossing the median plane of the segment below said common center 30 where the type bars converge and at the lowest point below the printing point.
18. In a front strike typewriting machine, the combination of a series of upwardly and rearwardly striking type bars all pivoted 35 in the same upright plane and the body portions of all of which converge at a common center below the printing point, the distance between the pivotal center of a type bar and said common center being uniform for all 40 of said type bars, and a segment having bearing slots in which said type bars are pivoted, the planes of the slots of each pair of corresponding bars at opposite sides of the segment converging at the median plane 45 of the segment and the planes of the slots for other such pairs of bars converging at different points in said median plane, the planes of the terminal slots converging at the greatest distance from the printing 50 point.
19. In a front strike typewriting machine, the combination of a series of upwardly and rearwardly striking type bars all pivoted in the same upright plane and the 55 body portion of all of which converge at a common center below the printing point, the distance between the pivotal center of a type bar and said common center being uniform for all of said type bars, and a segment having bearing slots in which said type bars are pivoted, the planes of the slots of each pair of corresponding bars at opposite sides of the segment converging at the median plane of the segment, the planes of the slots for different pairs of corresponding bars converging at different points along said median plane and at increasing distances below said common center, the slots for the two uppermost side bars converging at the lowest point. 70
20. In a typewriting machine, the combination of a series of segmentally arranged type bars, and a segment having bearing slots in which said type bars are pivotally mounted, the planes of the slots for a plurality of the type bars at one side of the segment converging at one side of the median plane of the segment. 75
21. In a typewriting machine, the combination of a series of segmentally arranged type bars, and a segment having bearing slots in which said type bars are pivotally mounted, the planes of the slots for a plurality of the type bars at one side of the segment converging at one side of the median plane of the segment, the body portion of each of said plurality of bars being bent laterally from the plane of its slot and all of the said series of type bars converging at a common point in the median plane of the segment. 80
22. In a typewriting machine, the combination of a series of segmentally arranged type bars, and a segment having bearing slots in which said type bars are pivotally mounted, the planes of the slots for a plurality of the type bars at one side of the segment converging at that side of the median plane of the segment where said plurality of type bars are mounted, the planes of the bearing slots for a plurality of type bars at the other side of the segment converging at the corresponding side of said median plane. 100
23. In a typewriting machine, the combination of a series of segmentally arranged type bars, and a segment having bearing slots in which said type bars are pivotally mounted, the planes of the slots for a plurality of the type bars at one side of the segment converging at that side of the median plane of the segment where said plurality of type bars are mounted, the planes of the bearing slots for a plurality of type bars at the other side of the segment converging at the corresponding side of said median plane. 105
24. In a typewriting machine, the combination of a series of segmentally arranged type bars, and a segment having bearing slots in which said type bars are pivotally mounted, the planes of the slots of each pair of corresponding bars at opposite sides of the segment converging at the median plane of the segment, the planes of the slots for different pairs of corresponding bars converging at different points along said median plane and at increasing distances below said common center, the slots for the two uppermost side bars converging at the lowest point. 110
25. In a typewriting machine, the combination of a series of segmentally arranged type bars, and a segment having bearing slots in which said type bars are pivotally mounted, the planes of the slots for a plurality of the type bars at one side of the segment converging at one side of the median plane of the segment, the body portions of all of the said series of type bars being bent laterally from the plane of its slot and the body portions of all of the type bars converging at a single point. 115
26. In a typewriting machine, the combination of a series of segmentally arranged type bars, and a segment having bearing slots in which said type bars are pivotally mounted, the planes of the slots for a plurality of the type bars at one side of the segment converging at that side of the median plane of the segment where said plurality of type bars are mounted, the planes of the bearing slots for a plurality of type bars at the other side of the segment converging at the corresponding side of said median plane, each type bar mounted in one of said converging slots having its body portion bent laterally from the plane of its slot and the body portions of all of the type bars converging at a single point. 120
27. In a typewriting machine, the combination of a series of segmentally arranged type bars, and a segment having bearing slots in which said type bars are pivotally mounted, the planes of the slots of each pair of corresponding bars at opposite sides of the segment converging at the median plane of the segment, the planes of the slots for different pairs of corresponding bars converging at different points along said median plane and at increasing distances below said common center, the slots for the two uppermost side bars converging at the lowest point. 125
28. In a typewriting machine, the combination of a series of segmentally arranged type bars, and a segment having bearing slots in which said type bars are pivotally mounted, the planes of the slots for a plurality of the type bars at one side of the segment converging at one side of the median plane of the segment, the body portions of all of the said series of type bars being bent laterally from the plane of its slot and the body portions of all of the type bars converging at a single point. 130

mounted, the planes of the slots for corresponding bars at opposite sides of the segment converging at the median plane of the segment and the planes of a plurality of 5 slots at each side of the segment converging at a point to one side of said median plane.

25. In a front strike typewriting machine, a series of upwardly and rearwardly swinging type bars pivoted on a common arc-shaped pivot wire, the body portions of all 10 of said bars when in printing position radiating from a common center below the printing point, and having the heel or pivot 15 end portion of a type bar swinging in a plane that passes through the middle of the type bar system below said common center.

26. In a typewriting machine, a series of sheet metal type bars pivoted on a common 20 arc-shaped pivot wire and all of which meet at a common center, the type carrying end of each of said bars being bent laterally, and the heel or pivot end portion thereof being bent at an angle to its body portion

and moving in a plane off-set inwardly from 25 said common center and extending intermediate said common center and the pivot wire.

27. A sheet metal pivoted type bar having a lateral bend at its free end portion to provide a stem on which the type block 30 is mounted and where such bar and the other bars of the system converge when in printing position, and also having a slight lateral bend between the body portion of the bar and the flat heel or pivot end portion thereof, so that the heel of the bar swings in one plane and its body portion in another plane, the plane of the heel extending inwardly from the printing point at a greater distance therefrom than the 40 plane of the body portion of the bar.

Signed at Ilion, in the county of Herkimer and State of New York, this 31st day of May, A. D. 1921.

GEORGE A. SEIB.
